DUST CART

Otto Ballert, Berlin, Germany

Application July 18, 1939, Serial No. 285,207
In Germany July 14, 1938

11 Claims. (Cl. 214—67)

This invention relates to a dust cart, in which the refuse is dumped at the rear of the cart through a hopper or opening into a dumping chamber and is pressed into the interior of the cart by means of a rudder-like wall member, which is adapted to be rocked about an axis, or an oscillatory rudder-like plunger, in such a way that by reason of the refuse added upon each oscillation of the plunger the entire space of the cart is gradually filled out, and at the same time, during the filling action, and particularly in the final stages thereof, the refuse is caused to be compressed.

Dust carts of this character have already been proposed heretofore. In the known arrangements the oscillatory rudder-like plunger or the oscillatory wall member is disposed in an upright position on a level with the horizontal bottom of the cart. The oscillatory plunger is firmly connected to a vertical shaft or column, which is mounted at its two ends on the top and the bottom of the cart and is mechanically driven.

This known arrangement is accompanied by certain disadvantages as follows: Owing to the disposal of the oscillatory plunger vertically with respect to the horizontal bottom of the collecting chamber, which plunger for normal conditions must have a certain minimum height and above which a sufficiently high filling space must be available below the dust bin from which the refuse is dumped, the hopper or opening for the introduction of the refuse requires to be situated some considerable height above the ground. This, of course, is a disadvantage in the dumping of the refuse, as the dust bins then require to be lifted accordingly.

The dumping space below the dust bin being emptied should not be too small, as the air displaced upon the dumping of the refuse should be allowed to escape readily without whirling up the dust, and this can only be accomplished by providing the dumping chamber with a certain minimum volume. Further, in the known arrangement of the oscillatory plunger the pressing of the refuse into the inner collecting chamber is also accomplished by difficulties, as in view of the horizontal movement of the refuse along the bottom of this chamber a filling of the latter is only possible after the accumulating refuse has been compressed to such extent that it is lifted up the end wall of the collecting chamber by reason of its inherent pressure. With this arrangement a complete filling of the collecting chamber at the rear end of the cart in the vicinity of the oscillatory plunger is practically impossi-

ble despite the use of a considerable amount of force. Considerable difficulties are also encountered in the discharge of the refuse; as the rotary column, which is mounted on the body of the cart itself and to which there is secured the oscillatory plunger, greatly obstructs the removal of the refuse upon the discharge of the cart by tilting towards the rear.

These disadvantages are undoubtedly responsible for the fact that this type of construction, despite its other advantages, has never been put into practice, and that this solution of the problem has again been dropped entirely.

The disadvantages aforesaid are eliminated by the invention. The latter resides principally in the fact that the preferably hydraulically driven rotary column together with the oscillatory wall or plunger firmly connected thereto is arranged or mounted on the upwardly sliding or liftable closure member at the rear of the body of the cart, and that the column is not disposed vertically with respect to the horizontal bottom of the collecting chamber, but slopes towards the rear corresponding to the sloped bottom of the dumping space within the upwardly sliding or liftable closure member, on which bottom the column is vertically mounted. In this way it is accomplished that without decreasing the height of the dumping chamber the hopper or opening through which the refuse is dumped can be located at a considerably lower level as compared with the known arrangements, so that difficulty in lifting the dust bins is greatly reduced. The sloping bottom within the dumping chamber is responsible for the fact that the rear end of the collecting chamber bottom, which connects up with the bottom of the dumping chamber without a break substantially in the entire breadth of the latter, is also sloped and ascends up to a certain point above the rear axle of the cart; from which point it again descends to the level of the horizontal bottom of the collecting chamber proper. In consequence the refuse is distributed much more readily within the collecting chamber, and the latter is filled out completely up to its rear end under less pressure than that required in the case of the known construction.

Three embodiments of the invention are illustrated by way of example in the accompanying drawings, the one embodiment being designed for the use of standard dust bins, which are simultaneously actuated by the driving means for the oscillatory plunger, i. e., are emptied into the cart and again returned, whilst a second embodiment allows for the use of other than standard bins,

which are tipped into the cart by hand. The embodiments in question can be furnished with liftable or sliding closure members.

Figs. 1 and 2 are elevational views, partially in section, of the two embodiments aforesaid, wherein liftable tops are provided and the operating means for the column of the oscillatory member are located either at the top or the bottom.

Fig. 3 is a plan view of Fig. 1.

Fig. 4 is a plan view of Fig. 2.

Fig. 5 is a rear view of Fig. 1.

Figs. 6 shows the dust card according to Fig. 1 in the tipped position.

Figs. 7 to 10 illustrate a possible embodiment of the invention having a sliding closure member at the rear.

Fig. 7 is an elevational view of the dust cart, partially in section, in the normal upright position for the collection of refuse.

Fig. 8 is a partial plan view of Fig. 7.

Fig. 8a shows on enlarged scale a section taken through a guide for the sliding closure member on the line 8-8 in Fig. 7.

Fig. 9 is a rear view of the dust cart according to Fig. 7.

Fig. 10 is an elevational view, partially in section, of the dust cart according to Fig. 7 in the position in which the refuse is again discharged.

In the drawings, 1 is the collecting chamber, 2 the liftable or sliding closure member at the rear, and 3 the dumping chamber, in which there is mounted the hydraulically driven column 4 for the oscillatory wall member 5, which is firmly connected to the said column. The hydraulic driving means for the wall or plunger 5 is provided either at the lower or at the upper end of the column (Figs. 1 and 2, 6, 7 and 10). As shown by Figs. 4 and 8, there is provided for the hydraulic motor a fixed piston 6, over which there is arranged to reciprocate a cylinder 7, which at the piston rod 6a of the piston 6 is sealed in the usual fashion. The one outer portion of the cylinder is designed as or furnished with a toothed rack 8. The teeth of this rack mesh with a toothed segment 9, which in the case of a liftable closure member is mounted firmly on the driving column 4 for the oscillatory plunger 5, whilst in the case of a sliding closure member it is carried by a separate bearing 9a on the body of the cart (Fig. 10).

Fig. 11 is a plan view of the hydraulic drive on enlarged scale.

The hydraulic pump with the requisite control and reversing elements is designated 10. From the same pipes 11 lead to the hydraulic driving means for the oscillatory plunger. The details are not shown in the drawings.

The pipes for the tipping device 13 of the cart are designated 12. The control system, which does not form part of the present invention, is so designed that there can be actuated as desired either the tipping device with the discharge trap open or the refuse collecting device with the trap closed. If standard dust bins are provided the rocking arm for the bins is connected as represented in Figures 1 and 6 in the conventional manner to the oscillatory plunger, in such a way that upon each oscillation of the plunger the bin is moved in positive fashion, i. e., is tipped into the cart and again swung out, so that upon each oscillatory movement of the plunger refuse is conveyed into the collecting chamber.

In the embodiments of the invention equipped with a liftable closure member it is necessary in loading refuse into the collecting chamber to

provide a special locking means for the closure member, as otherwise the latter would be caused to lift. This locking means is not illustrated in Figs 1 to 6. In the embodiment of the invention equipped with a sliding closure member a special locking device can be dispensed with, as the forces occurring upon the filling in of the refuse and tending to move the closure member are taken up by the guide means for the closure member. In

Fig. 8a there are shown guide rolls. For raising the closure member there is provided a special hydraulic lifting device, which is accommodated in a narrow shaft at the top of the collecting chamber (Figs. 7 to 10). 14 is a cable or chain, the one end of which is secured at 15 to the lower portion of the sliding closure member and passes over a guide roll 16 and a loose roll 17 to the hydraulic cylinder 18, where the other end of the cable is secured at 19. The loose roll 17 is mounted in the piston rod 20, which is bifurcated at this point and is again guided at 20.

The sliding closure member 2 is guided along the two sides of the collecting chamber 1 by means of rolls 21. These rolls 21 run in arcuate U-section iron members 22, which are secured to the container 1. For the purpose of sealing the closure member on the collecting chamber 1 U-section members 23 are secured to the closure member corresponding to the members 22. On the members 23 there are provided brackets 24 having axle pieces 25 for the rolls 21.

The hydraulic lifting device for the sliding top according to Figs. 7 to 10 is connected, without the interposition of control elements, to the same pressure source as the tipping device for the container 1. The dimensions are such that a tipping of the collecting chamber does not take place until the closure member has been fully raised. Similar dimensions also apply to the collecting chamber with liftable closure member in accordance with Figs. 1 to 6, in which, however the parts involved have not been specifically shown.

What I claim as new and desire to secure by Letters Patent is:

1. A dust cart of the character described, comprising a tiltably mounted body member formed as a collecting chamber, a closure member movably associated to the rear of said body member and having a dumping chamber arranged therein, said dumping chamber having a flat rearwardly sloping bottom adapted to match a correspondingly sloped adjacent bottom part of said collecting chamber substantially in the entire breadth of the latter and also comprising an oscillatory rudder-like member mounted in said closure member so as bodily to move therewith and having its axis of oscillation sloped towards the rear of said closure member, so that said axis is perpendicular with respect to the flat rearwardly sloping bottom part of said dumping chamber and to the adjacent sloping rear end of the collecting chamber bottom, said rudder-like member being adapted to perform a reciprocatory angular motion in said dumping chamber to convey refuse in a general upward and forward direction from said dumping chamber into said collecting chamber.

2. A device according to claim 1, in which a column is provided for supporting and actuating said oscillatory rudder-like member, said column being mounted in said movable closure member so as bodily to move therewith and having its axis of oscillation sloped towards the rear of said closure member, and in which driv-

ing means and a gear are provided adapted to impart a reciprocatory oscillation to said column, said gear being located at the one end of said column for transmitting the power from said driving means to said column.

3. A device according to claim 1, in which a column is provided for supporting and actuating said oscillatory rudder like member, said column being mounted in said movable closure member so as bodily to move therewith and having its axis of oscillation sloped towards the rear of said closure member, and in which a toothed segment is associated with the said column and a hydraulic motor is arranged having a toothed rack adapted to engage with the said segment, so as to impart a reciprocatory oscillation to said column and to said rudder-like member supported on and actuated by said column.

4. A device of the character described, comprising a body member formed as a collecting chamber, a closure member movably associated to the rear of said body member and having a dumping chamber arranged therein, an oscillatory rudder-like member adapted upon its oscillation to convey refuse from the said dumping chamber into said collecting chamber, said closure member being adapted to slide upwards at the rear of the said collecting chamber, a hydraulic lifting device for the said closure member disposed in the upper part of the said collecting chamber, a driven column supporting and actuating the said oscillatory member, driving means for the said column, and a hydraulic tipping device for emptying the said collecting chamber, the said lifting device and the said tipping device being connected to a common pressure source and the said lifting device being so dimensioned that it completes the lifting of the said closure member before the said tipping device enters into operation.

5. A device of the character described, comprising a body member formed as a collecting chamber, a closure member movably associated to the rear of said body member and having a dumping chamber arranged therein, an oscillatory rudder-like member adapted upon its oscillation to convey refuse from the dumping chamber into the collecting chamber, a driven column supporting and actuating the said oscillatory member, the said column being mounted in the said closure member, a toothed segment in association with the said column, and driving means for the said column comprising a fixed piston and a piston rod extending from the piston in both directions, a cylinder moved hydraulically with respect to the said piston and piston rod, and a toothed rack on the outer side of the said cylinder adapted to engage with the said segment.

6. A device according to claim 5, in which the said movable closure member is adapted to be lifted upwards together with the said oscillatory member and the said column from the rear of the said collecting chamber, and in which a gear is provided for transmitting power from the said driving means to the said column

which is located at the upper end of the said column.

7. A device according to claim 5, in which the said movable closure member is adapted to be lifted upwards together with the said oscillatory member and the said column from the rear of the said collecting chamber, and in which a gear is provided for transmitting power from the said driving means to the said column which is located at the lower end of the said column, and in which a bin and means are provided in association with the driving column for tipping and returning the bin conjointly with the oscillatory movement of the said oscillatory member.

8. A device according to claim 5, in which the said movable closure member is adapted to slide upwards together with the said oscillatory member and the said column at the rear of the said collecting chamber.

9. A device of the character described, comprising a body member formed as a collecting chamber, a closure member movably associated to the rear of said body member and having a dumping chamber arranged therein, an oscillatory rudder-like member adapted upon its oscillation to convey refuse from the said dumping chamber into the said collecting chamber, said closure member being adapted to slide with its side edges over the rear edges of the collecting chamber, rolls interposed between the said edges to assist the sliding action, a driven column supporting and actuating the said oscillatory member, the said column being mounted in the said closure member, and driving means for the said column located at the one end of the said column.

10. A device according to claim 9, in which a hydraulic lifting device is provided disposed in the upper part of the said collecting chamber, and means are provided connecting the hydraulic device to the lower portion of the said closure member for the purpose of lifting the said closure member.

11. A device of the character described, comprising a body member composed of collecting and dumping chambers and an oscillatory member, said collecting chamber being associated with the dumping chamber and the oscillatory member being adapted upon its oscillation to convey refuse from the said dumping chamber to the said collecting chamber, a closure member adapted to slide upwards at the rear of the said collecting chamber, a hydraulic lifting device for the said closure member disposed in the upper part of the said collecting chamber, a driven column supporting and actuating the said oscillatory member, driving means for the said column, and a hydraulic tipping device for emptying the said collecting chamber, the said lifting device and the said tipping device being connected to a common pressure source and the said lifting device being so dimensioned that it completes the lifting of the said closure member before the said tipping device enters into operation.

OTTO BALLERT.
